CLAIM

The ornamental design for a label printer, as shown and described.

DESCRIPTION

FIG. 1 is a front perspective view of a label printer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The dash-dash broken lines shown in the drawings represent portions of the label printer that form no part of the claimed design. The dash-dot-dash broken lines encircling the enlarged views are for annotative purposes only and form no part of the claim design.

1 Claim, 9 Drawing Sheets(56)
